UNITED STATES PATENT OFFICE.

EDWARD C. TERRY, OF HARTFORD, CONNECTICUT, ASSIGNOR TO THE PHOENIX BRASS FOUNDRY COMPANY, OF SAME PLACE.

FLOAT MECHANISM FOR OPERATING VALVES.

SPECIFICATION forming part of Letters Patent No. 549,548, dated November 12, 1895.

Application filed June 19, 1895. Serial No. 553,358. (No model.)

To all whom it may concern:

Be it known that I, EDWARD C. TERRY, a citizen of the United States, and a resident of Hartford, in the county of Hartford and State 5 of Connecticut, have invented certain new and useful Improvements in Float Mechanism for Operating Valves, of which the following is a full, clear, and exact description, whereby any one skilled in the art can make and 10 use the same.

The object of my invention is to provide a device by means of which the rate of movement of a float may be utilized in such manner as to secure the quick closing of a valve 15 at a desired time; and to this end my invention consists in the details of the several parts making up the float mechanism and in its combination with a valve, as more particularly hereinafter described, and pointed out in the 20 claims.

Referring to the drawings, Figure 1 is a detail view in elevation of a tank fitted with an inlet-valve and float mechanism, showing the latter when the tank is empty, the valve and 25 tank being cut in vertical section. Fig. 2 is a view in section of a tank, showing the valve and float mechanism in side elevation and the latter just before the water reaches the auxiliary float. Fig. 3 is a like view of the 30 device, showing the position of the parts with the float lifted and the valve closed. Fig. 4 is an end view of the valve and float mechanism.

The invention is herein described in connection 35 with a supply-valve or ball-cock such as is commonly used on a tank; but it is not limited to the particular form of mechanism shown herein nor to the particular combination of the parts described.

In the accompanying drawings the letter *a* denotes a tank adapted to contain water and provided with any convenient form of discharge-valve. An inlet-pipe *b* is provided 40 with a valve *c*, which is operated by means of a float *d*, connected to the valve by the lever *e*.

In the form shown the valve-spindle *c* has a projecting arm *c*² extending through a slot in the side of the valve-body and connected 45 to a pivot to a link *f*. This link is also connected by a pivot-pin *f*' to a rock-shaft *g*,

which is mounted in a bracket on the valve-case. The inner end of the float-lever *e* is secured to the rock-shaft in such position that when the valve is open and the tank empty 55 the float is suspended from the rock-shaft in a substantially vertical position. In this position the float mechanism is on the center so far as any upward pressure is concerned, and the rock-shaft can be turned only by swinging 60 the float and lever off the center and out of the upright position against the stop *i*. When the float is in this position, water may flow into the tank and fill it without causing the float to change its position, although the 65 buoyancy of the float will, as soon as the water has left it so as to submerge it, put the float into a condition of unstable equilibrium. If at this time any force is brought into play to move the float and lever slightly off the center, the buoyancy of the float is brought 70 quickly into play, and the latter lifts under the pressure due to the rising of the water above the level of the float. This upward movement of the float will be more or less 75 rapid, according to the distance that the water has risen above the float before the latter is moved into a position to permit the buoyancy of the float to operate.

In order to move the float off the center, a 80 supplemental or auxiliary float *h* is preferably employed, and it is secured to the float-lever by a clamp device *h*', as a binding-screw, which provides for an adjustment of the auxiliary float along the lever. By this means the exact 85 point at which the main float is to be thrown off its center by the rising of the water can be determined and the movement of the main float controlled at the proper time when the sudden closing movement of the float 90 is desired. The main object of securing this quick closing of the valve is to overcome the tendency in prior structures where a float is utilized to operate a valve to dwell on the closing movement and allow a disagreeable hissing sound to be made, the same slow closing 95 of the valve having a tendency to permit the parts of most valves to chatter and add to the disturbance in the closing movement of the valve.

In my improved float mechanism provision is made for the quick closing of the valve at

a time when the tank is practically filled to the desired limit, and by such quick closing all noise incident to the operation of prior devices is effectually eliminated.

5 It is obvious that the main feature of my invention embodies mechanism by means of which a float is held submerged in the rising water until a certain predetermined time, when the buoyancy of the float is taken advantage of by a connected part and a quick movement of the float, caused by the exertion of the buoyant force. It is obvious that this result can be attained by other combination of parts than those herein described, and I
15 do not limit myself to the parts shown nor to the specific combination. It is possible in this connection to make use of a float that has a water-chamber provided with a valve, adapted to empty as the water flows out of the tank
20 and to be refilled only when the water has risen above the level of the float, such refilling disturbing the equilibrium of the float and causing it to rise quickly in response to the buoyant force.
25 Other forms of mechanism embodying means for overbalancing or tripping the float may be used without departing from the main feature of my improvement, which consists, as stated, in the idea of and means for holding
30 the float mechanism on the center until such time as it may be desired to relieve the float.

I claim as my invention—

1. In combination with a tank, a valve appurtenant to the supply pipe for the tank, a
35 float lever pendent from a pivot and held substantially vertical when the tank is empty, and means for moving the pendent float off the

center and thereby bringing its buoyancy into operation when the float has been submerged in the inflowing water, all substantially as described.

2. In combination with a tank, a supply pipe, a valve in the supply pipe, a float mechanism connected to the valve and including a float lever connected to the valve and adapted to hang in a substantially upright position when the tank is substantially empty, and a supplemental float held on an arm projecting from the main lever, all substantially as described.

3. In combination with a tank, a supply pipe, a valve in the supply pipe, a float mechanism connected to the valve and including a float lever connected to the valve and adapted to hang in a substantially upright position when the tank is empty, and a supplemental float held on an adjustable arm projecting from the main lever, all substantially as described.

4. In combination with a tank, a supply pipe, a valve appurtenant to the supply pipe for the tank, a float lever connected to the valve and adapted to hang from its pivot in a substantially vertical position when the tank is empty, and means exclusive of any positive lock and catch mechanism for directly moving the float off the center and thereby bringing its buoyancy into operation when the float has been submerged in the inflowing water, all substantially as described.

EDWARD C. TERRY.
